UNITED STATES PATENT OFFICE.

WILLIAM H. CRAUN, OF HOBOKEN, NEW JERSEY, AND PAUL MATHIS, OF BROOKLYN,
NEW YORK.

PORTABLE LATHE FOR RECUTTING CRANK-SHAFT PINS.

1,345,138.

Specification of Letters Patent. Patented June 29, 1920.

Application filed June 10, 1919. Serial No. 303,017.

To all whom it may concern:

Be it known that we, WILLIAM H. CRAUN and PAUL MATHIS, citizens of the United States, residing, respectively, at Hoboken, 5 in the county of Hudson and State of New Jersey, and Brooklyn, county of Kings, and State of New York, have invented certain new and useful Improvements in Portable Lathes for Recutting Crank-Shaft Pins, of which the following is a specification.

This invention relates to machines for recutting crank shafts, and pertains especially to a portable lathe applicable to crank shafts without removing such shafts from their 15 mountings or working position for reshaping, recutting or returning the crank member.

The prime object of the invention is to provide a portable lathe of special design 20 applicable to crank shafts, especially the crank shafts of ships, for truing the worn crank member of such shafts without displacing or removing the shafts for such purpose.

A further object of the invention is to provide a machine of such construction and arrangement of parts as to be applied to crank shafts of various size, and as to be adjustable bodily and in its parts with respect to the crank member of such shafts 30 for reshaping said member without removing the shaft from its bearings.

A still further object of the invention is to provide in a portable lathe for recutting 35 crank shafts, a special tool carriage, and means for revolving the carriage around the crank member of such shafts in a recutting operation.

A still further object of the invention is 40 to provide, in a portable turning lathe, devices affording means for reversing the position of the cutting tool holder from one side to the other of the lathe, devices for adjusting the tool head, and devices affording means for reversing the feed mechanism.

A still further object of the invention is 45 to provide peculiar mechanism for transmitting power from a power source for rotary movement of the tool-carrying ring, and to furnish a peculiar crank shaft clamping yoke or frame having journal bearings for certain screw rods and shaft members of the lathe.

Various other novel and peculiar devices 50 are embodied in the invention, and various other objects, advantages and improved re-

sults are attainable in the practical application of the invention, as will be hereinafter set forth.

In the accompanying drawings forming 60 part of this application:

Figure 1 is an end view of a crank shaft showing the application of the invention.

Fig. 2 is an edge elevation of part of what is shown in Fig. 1.

Fig. 3 is a cross section showing the application of the invention as in crank pin cutting.

Fig. 4 is an edge elevation of the lathe partly broken away.

Fig. 5 is a detail end view of the tool carriage as set into the ring gear.

Fig. 6 is a detail longitudinal section of part of the tool carriage showing means for sliding the shoes.

Fig. 7 is a detail sectional view of one of the segment gears taken through one of the bearings 21 and showing one of the sleeves 19 at the extreme limit of its movement on one of the screw shafts with a sprocket 80 wheel in elevation.

Fig. 8 is a detail section showing one of the bearings between the tool carriage ring and the outer fixed ring.

Fig. 9 is a detail sectional view of the tool holder.

Fig. 10 is a detail perspective view of a tool holder member.

Fig. 11 is a detail perspective view of two interlocking parts of the tool holder.

Fig. 12 is a detail sectional view of the pinion 6 and its housing showing the ring gear meshing therewith and partly broken away.

Fig. 13 is an elevation showing a modification of the clamping yoke.

Fig. 14 is a detail elevation showing a further modification.

The same reference characters denote the same parts throughout the several views of 100 the drawings.

We are fully aware that certain devices have been patented for recutting or reshaping the crank members of crank shafts without displacing such shafts, but such devices 105 are inadequate in that they are incapable of true cutting throughout the surface of the crank members, that they are incapable of proper and necessary adjustment to perfect such cutting, that they do not provide 110 for reversing the tool post from one side to the other of the revolving ring, and that

they do not provide for true alinement of the tool post for continuing the cut from one end to the other of the crank members. It is, therefore, the purpose of our invention to provide a lathe embodying such devices and coöperating parts as will result in true adjustment of all the parts for making a true recutting of worn or imperfect crank members, and to insure the rendition of the crank members in perfect resurfacing condition without removing or displacing such shafts.

In carrying out our invention, we employ a two part outer casing ring 1, clamped together by suitable bolts 2, and having side flanges 3 forming a raceway for a two part gear wheel 4 clamped together by bolts 5, and meshing with a pinion 6 revolvably secured in a housing 7 of the ring 1 and slidably keyed to a shaft 8, having a driven pulley 8^a. The ends of the shaft 8 are held in bearings 7^a, of special hangers. The ring 1 has three peripheral bearings 9 for guide rods 10, the ends of which are secured in bearings 11 of a pair of centering hangers 12 adapted to be secured to the outer face and periphery of the crank arms 13 of a crank shaft 14 by means of single heads 15 having set bolts 15^a, a double head 16 having set bolts 16^a and a centering bolt 16^b which engages a center opposite the crank pin or member 17 so as to centralize the ring 1 and the gear 4 with and around said member. Feed screws 18 have each end secured in the frames 12 and mesh with screw sleeves 19 and 19^a revolvably secured by keepers 20 in housings 21 on the periphery of the ring 1, so that the latter and the carriage ring 4 may be fed lengthwise the crank shaft during the revolution of said ring gear. A beveled gear 22 is secured to the sleeves 19 and meshes at intervals with beveled toothed segments 23 secured to the face of the ring gear 4, whereby the sleeves 19 are turned on the screws 18 one revolution to six revolutions of the gear 4, in crank pin turning or recutting operations, as will be hereinafter more fully explained.

To insure uniform slide feeding of the lathe the screw sleeves have attached thereto a sprocket wheel 24 for a sprocket chain 25 which transmits driving power from a sprocket wheel 26 on one end of the shaft 8 to the sleeves 19 and 19^a on the screw shafts 18. These sprocket wheels and chain are on the outer side of one of the hanger frames 12, and are essential in true sliding movement of the lathe. The tool carriage is mounted on and within the ring gear 4 by means of an angular plate 27 secured to lugs 28 on the inner periphery of the gear 4 by set bolts 29. The plate 27 has ribs 30 under which a bottom flange 31 of slidable shoes 32 engage, and a like shoe flange 33 engages over ribs 34 on a head block 35

having depending arms 36 which suspend a pinion 37 and a gear 38 meshing with similar gears 39 on the ends of a right and left screw threaded rod 40 having the shoes 32 slidably screwing thereon, so as to raise and lower the head block in setting the tool for a cut preparatory to starting the lathe in slide feeding. The ribs converge inwardly on an incline, and the rod 40 has a central disk 41 working in bearings 42 formed central of the block 35 and web 36 of the plate 27. The pinion 37 meshes with a segment rack 43 pivoted to the face of the ring 1 at 44, and fulcrumed by means of a bolt 45 extending through a slot 46 in the rack, and the free end of the rack 43 has a hand rod 47 connected therewith and working through keepers 48, and cushioned by a spiral spring 49. The rack 43 has a slot 50 of sufficient width to permit the rack to be adjusted by the hand rod 47 for having either the rack teeth 51 or the rack teeth 52 mesh with the pinion 37 for advancing and reversing the travel of the shoes 32 by the gears 38 and 39 on the shoe rods 40, which results in raising and lowering the head block 35, upon which the holder 53 for a tool as 54 is mounted.

The tool holder 53 comprises a member 54^a having a stem 55 fitting a socket 56 in each end of the block 35, and said ends have grooves 57 into which fit projections 58 on the inner face of the member 54^a so as to afford adjustment of the member 54^a on the ends of the block 35 with the stem 55 as a pivot, and said member 54^a is secured in adjusted position by set bolts 59. The tool holder also embodies means for adjusting the tool without moving or adjusting the member 54^a, and said means consists of an inner disk 60 having a central socket 61 in which the tool is secured as by a set bolt 62, and the disk has a plurality of prongs 63 projecting from the upper face and fitting cavities 64 in the member 54^a. The disk 60 is held in position by a screw bushing 65 having a projecting end 66 to which may be applied a wrench for operating the bushing so as to permit the disk 60 to be turned for adjusting the tool. It will be seen that the member 54^a may be changed from one end to the other of the block 35 without displacing or altering the position of the tool, for the purpose of continuing a true cut first started by the tool at one end of the crank pin and finished at the other end of the crank pin. This is an important feature for the reason that a cut as first started by the tool moving in one direction over the crank pin to its limit in said direction is continued by merely changing the post or tool holding member 54^a to the opposite end of the block 35 and reversing the movement of said block. Such operations are obviously repeated if necessary until the crank 130

pin has been fully and desirably recut and finished.

The tool carriage is revolved around the crank pin by the ring 4, and during such revolution the pinion 37 travels in the rack 43 for radially moving the tool while the tool is moved lengthwise the crank in a cutting operation by the gear 22 and the segments 23, and the movement of the tool is reversed by operating the rack 43 with the hand rod 41. This reversement may be made without stopping the lathe. When the tool block 35 has carried the tool in a cutting operation to the limit in one direction the lathe is stopped and the tool holder is changed to the opposite end of said block for reverse movement without changing or adjusting the position of the tool in its holder. In order to provide against frictional wear and resultant lost motion between the ring 1 and the gear ring 4, we form a V-shaped annular bearing 70 on the outer periphery of the ring 4, and said bearing works in a V-shaped annular bearing 71 in an open ring 72 adjustably secured to the periphery of the ring 1 between the rings 1 and 4 by means of screw bushings 73. Obviously by operating the bushings the bushing ring 72 will take up any lost motion between the rings 1 and 4, so as to keep the rings 1 and 4 always centralized.

Referring to the modification shown in Fig. 13 of the drawings, the shaft hanger may have attached thereto an extension 75 for holding an additional clamping head in duplication of the head 16.

Referring to the modification shown in Fig. 14, differential gears may be utilized in lieu of the pulley 8^a, for gearing the lathe with driving power. In order to employ such differential gears, we provide the shaft 8 with a driven gear wheel 77 meshing with a gear wheel 78 which meshes with a gear wheel 79. The wheels 78 and 79 are journaled in a frame 80 slidably secured in slots 81 of the hanger arms 82 for the purpose of moving the intermediate wheel 78 out of mesh with the wheel 77 so as to substitute larger or smaller wheels for the wheels 78 and 79 according to the speed produced on the wheel 77 by various driving power connections.

Obviously various other duplications, mechanical changes and arrangements in and combination of the several parts of the invention may be made in manufacture and assembling the same, therefore we do not wish to limit ourselves in these respects, nor do we wish to be understood as confining the application of the machine only to crank shafts, but reserve the right to make such changes in the parts and in the construction and assembling thereof, and in various applications of the machine, as may not be inconsistent with the appended claims.

Having thus described our invention what we claim as new and desire to secure by Letters Patent is:

1. In a portable lathe applicable to crank shafts for recutting the pins thereof, a casing adapted to encircle the shaft, screw shafts fixed against lengthwise movement and having the casing mounted thereon for longitudinal movement, a ring gear revolvable in the casing during said longitudinal movement, a tool carriage secured to the inner periphery of the ring gear, means for operating said gear, and means operated by the ring gear for feeding the carriage radially. 70

2. In a portable lathe for recutting crank pins, a tool carriage, a gear ring upon which the carriage is secured for revolving the carriage, carriage mechanism operated by the ring for feeding the tool radially, mechanism operated by the ring for feeding the tool longitudinally during the revolution of the carriage in a pin cutting operation, and means attachable to the crank for permitting said movements. 80

3. In a portable lathe for recutting crank pins, a revolvable gear ring, a tool carriage secured to the ring and comprising a pair of slidable shoes operated by the ring for feeding the tool radially, and means for operating the ring. 95

4. In a portable lathe for recutting crank pins, a non-revolvable casing, a gear ring revolvable in the casing, means operated by the ring for feeding the casing longitudinally, a tool carriage secured to the ring, and means operated by the ring for feeding the tool radially. 100

5. A revolvably driven gear ring, a tool carriage secured within the ring and having a head block for raising and lowering the tool to set the latter to cut, and a tool holder adapted to be changed from one end to the other of said block without changing the position of the tool with respect to the holder. 105

6. A tool carriage head block having socket ends, screw operated shoes for raising and lowering the block with respect to the carriage, and a tool holder having a stem fitting the sockets for reversing the position 115 of the holder without altering the position of the tool with respect to the holder.

7. In a tool carriage the combination with a head block having ends for applying a tool holder, of a tool holder having a face adjustably fitting said ends, and means within the holder for adjusting the tool therein independent of said holder adjustment. 120

8. In means for adjusting a lathe turning tool, a tool carriage having shoe guides, a tool carriage head block having like guides, shoes engaging the guides and connecting the block with the carriage, and means for sliding the shoes between the block and the carriage for raising and lowering the block. 125

130

9. In means for operating a lathe turning tool, a revolubly driven ring gear, a tool carriage secured to the ring and embodying a vertically adjustable head block, means for adjusting the block for cut-setting the tool, a tool holder adjustably securable to the ends of the block, means within the holder for adjusting the tool therein independent of the block adjustment, and means for sliding said ring gear in a cutting operation of the tool.
10. In means for operating a lathe turning tool, a revolubly driven ring gear, a tool carriage secured to the ring and embodying a vertically adjustable head block, a tool holder adjustably securable to the ends of the block, means within the holder for adjusting the tool therein independent of the block adjustment, a plurality of slidable shoes, screw rods operating the shoes for adjusting said block, a train of gears connecting the screw rods, a pinion projecting from one of the gears of said train, a toothed segment adapted to mesh with said pinion for reversing the movement of the shoes, and means for sliding said ring gear in a tool cutting operation.
11. In a portable lathe for recutting crank pins, hangers adapted to be clamped to said crank for suspending the ring around the pin, screw shafts having their ends anchored in the hangers, a screw sleeve retained by said ring and meshing with the screw shafts for sliding said ring, a gear ring revolvably contained in the casing ring and having a cutting tool mounted therein, a pinion retained in the casing ring and meshing with the gear ring, a driven shaft having said pinion slidably keyed thereto, and a gear device connecting the ring gear with the sleeve and turning the latter for sliding said rings in a tool feeding operation.
12. In a lathe adapted to be applied to mounted crank shafts for recutting the crank pins, a pair of hangers adapted to be clamped upon the outer face of the crank arms and having means for centering the frames with the center of the pins, guide rods connecting the hangers, screw shafts anchored in the hangers parallel with said rods, a ring casing slidable on the rods, screw sleeves attached to the casing and meshing with the screw shafts for sliding the casing, a pinion mounted in the casing, a ring gear revolved in the casing by said pinion, a tool carriage secured in the ring gear, a driven shaft having said pinion slidably keyed thereon, means connecting the driven shaft with the sleeves for turning the latter, and means connecting all of said shafts for unison movement in a crank pin cutting operation.
13. The combination of a casing, a ring gear contained in the casing, means for revolving the gear, screw sleeves held by the

casing, anchored screw shafts meshing with the sleeves, a pinion secured to one of the sleeves, a segment gear secured to the ring gear and intermittently meshing with said pinion during the revolution of the ring gear for feeding the casing on the screw shafts.

14. In a portable turning lathe for recutting crank shaft pins, a ring gear revolubly driven around the pin, means for adjustably mounting a cutting tool on the gear, a feed pinion, a gear segment on the ring gear intermittently meshing with the pinion for feeding the gear during its revolution, and means for revolving the ring gear in a pin cutting operation.

15. In means for attaching a turning lathe to crank shafts for recutting crank pins, a pair of hangers having bearings, means projecting from the lathe into said bearings for suspending the lathe around a crank pin, and clamping devices securing the hangers to the crank arms for centralizing the lathe with respect to the crank pin.

16. The combination of an outer ring casing, a ring gear revolvably within the casing, a bearing ring between the casing and the gear, and means carried by the casing for controlling the bearing of the bearing ring on the gear ring.

17. The combination of a casing ring, a ring gear having an annular bearing protrusion, an open ring having a bearing for said protrusion, and a plurality of screw bushings working through the periphery of the casing ring for operating the split ring to compensate for lost motions between the casing ring and the ring gear.

18. The combination of an outer casing ring, a ring gear revolvably contained within the casing ring and having a beveled annular bearing projecting from its periphery, an open ring having a bearing surface for the beveled bearing, and means working through the periphery of the casing ring for adjusting the open ring relative to said beveled bearing.

19. The combination of a nonrevolvable casing ring, a ring gear revolvble in the casing ring and having an annularly projecting bearing, a bearing ring between the casing ring and the gear ring and having a groove fitting said annular bearing, and a plurality of bushings connecting the open ring with the casing ring and adapted to be adjusted for varying the bearing of the open ring on the said annular bearing.

In witness whereof we hereunto set our hands in the presence of two witnesses.
